Primary Examiner — Robert M Spear*Assistant Examiner* — Ryan Harvey(74) Attorney, Agent, or Firm — Dilworth & Barrese, LLP(57) CLAIM

The ornamental design for a gaming cloth for a gaming table, as shown and described.

DESCRIPTION

The sole FIGURE is a plan view of a gaming cloth for a gaming table showing my new design.

The broken lines in the drawings which define the bounds of the claimed design form no part thereof.

1 Claim, 1 Drawing Sheet(56)
